(57) **CLAIM**

The ornamental design for a combined container and label, as shown and described.

DESCRIPTION

FIG. 1 is a perspective view of a bottle container and label incorporating our new design;

FIG. 2 is a front elevational view thereof;

FIG. 3 is a rear elevational view thereof;

FIGS. 4 and 5 are side elevational views thereof;

FIG. 6 is a top plan view thereof; and,

FIG. 7 is a bottom view thereof.

The broken lines shown in the drawings are for illustrative purposes only and form no part of the claimed design.
